Primary Examiner — Ricky Pham(74) *Attorney, Agent, or Firm* — Brad M. Behar & Associates, PLLC(57) **CLAIM**

The ornamental design for a pan, as shown and described.

DESCRIPTION

FIG. 1 is a perspective view of an embodiment of a pan showing my new design;

FIG. 2 is a front view thereof, the back view being mirror images thereof;

FIG. 3 is a right side view thereof;

FIG. 4 is a top view thereof;

FIG. 5 is a bottom view thereof;

FIG. 6 is an enlarged cross sectional view along axis 6-6 thereof; and,

FIG. 7 is an enlarged view of a portion of the cross section thereof.

The broken lines shown in the drawings are for illustrative purposes only and form no part of the claimed design.
